UNITED STATES PATENT OFFICE.

ROBERT LEDING, OF WASHIINGTON, DISTRICT OF COLUMBIA.

DESIGN FOR A SPOON, &c.

SPECIFICATION forming part of Design No. 20,650, dated March 31, 1891.

Application filed March 5, 1891. Serial No. 383,916. Term of patent 7 years.

To all whom it may concern:

Be it known that I, ROBERT LEDING, a citizen of the United States, residing at Washington, in the District of Columbia, have invented 5 and produced a new and original Design for Spoons, of which the following is a specification, reference being had to the accompanying drawings, forming a part thereof, and wherein—

10 Figure 1 represents a front or obverse view of a spoon embodying my design, and Fig. 2 represents a rear or reverse view of the same.

The leading features of my design consist of medallion heads of George and Mary Washington, located at the end of the handle, together with the Washington crest beyond said medallion heads, and flags extending from the handle along the edges of the bowl, between which flags is a representation of the Washington house at Mount Vernon.

20 In the drawings, A is the handle.

B is the space occupied by the medallion heads.

C is the Washington crest beyond the medallion heads.

25 D are the flags along the edges of the bowl, between which flags will be seen a representation of the Washington house at Mount Vernon.

What I claim is—

1. The design for a spoon, as shown.
2. The design for the obverse of a spoon, as shown.
3. The design for the reverse of a spoon, as shown.

35 In testimony whereof I affix my signature in presence of two witnesses.

ROBERT LEDING.

Witnesses:

JOHN C. PENNIE,
WM. A. EASTERDAY.
